[57] CLAIM

The ornamental design for a double-sided suction cup for dinnerware, as shown and described.

DESCRIPTION

FIG. 1 is a perspective view of a double-sided suction cup for dinnerware showing my new design;

FIG. 2 is a front elevation thereof;

FIG. 3 is a rear elevation thereof;

FIG. 4 is a side elevation, the opposite side being a mirror image thereof;

FIG. 5 is a top plan view thereof; and,

FIG. 6 is a bottom plan view thereof.

*Fig. 1**Fig. 2**Fig. 3**Fig. 4*
